UNITED STATES PATENT OFFICE

MAX REINER, OF BRONX, NEW YORK, ASSIGNOR, BY MESNE ASSIGNMENTS, TO PERPETUAL SELF WINDING WATCH COMPANY OF AMERICA, INC., OF NEW YORK, N. Y., A CORPORATION OF DELAWARE

SELF-WINDING WATCH

Application filed February 8, 1929. Serial No. 338,395.

This invention relates to watches, more especially to wrist watches or the like provided with a self-winding movement whereby movement of the watch is effective to wind the main spring.

An object of this invention is a self-winding watch or the like provided with improved and effective means for effecting winding of the main spring by movement of the watch, while being worn and preventing overwinding of such spring.

According to this invention, the winding of the main spring is effected by means of a pendulum, oscillation of which is caused by motion of the watch, usually effected by movement of the wrist of the wearer of the watch. There is also provided a wheel to which uni-directional rotation is imparted by the pendulum, this wheel being connected to the winding train of the watch. The pendulum comprises an oscillatory arm having a weight pivoted to its free end. Positive means are provided to limit in one direction the swing of the weight about its pivot and yieldable or resilient means are provided for limiting the swing of the weight in the other direction. Thus, when the main spring approaches its winding limit, the arm of the pendulum remains stationary, while the weight oscillates about its own pivot, thus preventing over-winding of the watch. Means are provided for varying the tension applied to the resilient means so that the extent to which the main spring is wound may be varied, as desired.

Other objects, novel features and advantages of this invention will be apparent from the following specification and accompanying drawings, wherein

Fig. 1 is a rear view of a watch movement embodying the invention.

Fig. 2 is a partial section on the line 2—2 of Fig. 1, and

Fig. 3 is an enlarged perspective view of the pendulum.

The back plate 10 of a watch movement supports a bracket 11 and a shaft 12 has its ends journaled in the plate 10 and the bracket 11. An arm 13 and a gear wheel 14 are mounted on the shaft 12. Both the arm 13

and the gear wheel 14 may be rotatably mounted on the shaft or one may be rotatably mounted on the shaft and the other fixed to the shaft. A pawl 15 is carried by the arm 13 and engages with the teeth of the wheel 14 so that oscillation of the arm 13 effects uni-directional rotation of the wheel 14. The wheel 14 is connected through a suitable winding train with the main spring ratchet 16, so that rotation of the wheel 14 is effective to wind the main spring. A pawl 17 prevents backward rotation of the gear wheel 14.

A weight 18 is supported from the arm 13 by means of plates 19 extending upwardly from the weight and receiving a pivot pin 20 extending through the lower end of the arm 13. The plates 19 extend upwardly beyond the pivot pin 20 into a cut-out on the arm 13 thereby forming a positive stop to limit in one direction the swing of the weight about its pivot 20. Between the plates 19 is supported a disk 21 having a series of sockets 22 on its periphery. A leaf spring 23 is attached to the arm 13 by a screw 24 and has its free end resting in the exposed socket 22 of the disk 21. This spring acts as a yielding stop to limit in the other direction the swinging movement of the weight 18. The disk 22 is eccentrically mounted so that by rotating the same, the tension on the spring 23 may be varied. A guide 25 may be provided for the weight 18 to slide along as the pendulum 13 is oscillated, thus relieving the shaft 12 of strain when the watch is held in horizontal position. Pins or other suitable stops 26 are provided to limit the swinging motion of the pendulum. The guide and stops are not essential, but may be desirable for the proper functioning of the winding mechanism.

When the watch is being worn, the arm 13 and weight 18 constitute a pendulum which swings back and forth as the watch is moved. Uni-directional rotation is imparted to the gear wheel 14 and through the winding train to the main spring, whereby the latter is wound. Overwinding of the main spring is prevented by virtue of the fact that the weight 18 is pivoted to the end of the arm 13. Thus, when the main spring is nearly wound, its resistance to winding becomes superior to

the tension of the spring 23, whereupon the weight 18 swings about its own pivot without causing oscillation of the arm 13. In this way, overwinding is prevented. This 5 pendulum arrangement makes it possible to locate the axis of the pendulum at points other than the center of the watch, thereby obtaining for the pendulum the maximum leverage and also makes possible the use of 10 fewer gears in the winding train. Although the pendulum is shown as being mounted exterior of the movement, it may be mounted in the plane of the movement as well as at either side thereof.

15 It is, of course, understood that various structural changes may be made in the device above described, without in any way departing from the spirit of the invention as defined in the appended claims.

20 I claim:

1. In a self-winding watch, a two-part jointed pendulum, a wheel, means to impart uni-directional rotation to said wheel from said pendulum, a winding train operated by said wheel, and yieldable means carried by one part and engaging the other part for normally preventing flexion of said pendulum.
2. In a self-winding watch, a two-part jointed pendulum, a wheel, means to impart uni-directional rotation to said wheel from said pendulum, a winding train operated by said wheel, and resilient means carried by one part and engaging the other part normally to prevent flexion of said pendulum.
3. In a self-winding watch, a two-part jointed pendulum, a wheel, means to impart uni-directional rotation to said wheel from said pendulum, a winding train operated by said wheel, resilient means carried by one part and engaging the other part normally to prevent flexion of said pendulum, and means for varying the tension of said resilient means.
4. In a self-winding watch, a pivoted arm, a wheel, means to impart uni-directional rotation to said wheel from said arm, a weight pivoted to the free end of said arm, and yieldable means normally preventing oscillation of said weight about its pivot.
5. In a self-winding watch, a pivoted arm, a wheel, means to impart uni-directional rotation to said wheel from said arm, a weight pivoted to the free end of said arm, yieldable means normally preventing oscillation of said weight about its pivot, and means for varying the strength of said yieldable means.
6. In a self-winding watch, a pivoted arm, a wheel, means to impart uni-directional rotation to said wheel from said arm, a weight pivoted to the free end of said arm, and resilient means tending to prevent oscillation of said weight about its pivot.
7. In a self-winding watch, a pivoted arm, 65 a wheel, means to impart uni-directional ro-

tation to said wheel from said arm, a weight pivoted to the free end of said arm, resilient means tending to prevent oscillation of said weight about its pivot, and means for varying the tension of said resilient means.

8. In a self-winding watch, a pivoted arm, a wheel, means to impart uni-directional rotation to said wheel from said arm, a weight pivoted to the free end of said arm, positive means to limit in one direction the swing of said weight about its pivot, and yieldable means tending to limit the swing of said weight in the opposite direction.

9. In a self-winding watch, a pivoted arm, a wheel, means to impart uni-directional rotation to said wheel from said arm, a weight pivoted to the free end of said arm, positive means to limit in one direction the swing of said weight about its pivot, and resilient means tending to limit the swinging of said weight in the opposite direction.

10. In a self-winding watch, a pivoted arm, a wheel, means to impart uni-directional rotation to said wheel from said arm, a weight pivoted to the free end of said arm, positive means to limit in one direction the swing of said weight about its pivot, resilient means tending to limit the swinging of said weight in the opposite direction, and means for varying the tension of said resilient means.

11. In a self-winding watch, a two-part jointed pendulum, a wheel, means to impart uni-directional rotation from said pendulum to said wheel, a winding train operated by said wheel, and means carried by and tending to prevent relative movement of the pendulum parts.

12. In a self-winding watch, a two-part pendulum, a wheel, means to impart uni-directional rotation from said pendulum to said wheel, a winding train operated by said wheel, and means carried by and tending to prevent relative movement of the pendulum parts.

13. In a self-winding watch, a two-part pendulum, a wheel, means to impart uni-directional rotation from said pendulum to said wheel, a winding train operated by said wheel, and resilient means carried by one part and engaging the other part normally to prevent relative movement thereof.

14. In a self-winding watch, a two-part pendulum, a wheel, means to impart uni-directional rotation from said pendulum to said wheel, a winding train operated by said wheel, resilient means carried by one part and engaging the other part normally to prevent relative movement thereof, and means for varying the tension of said resilient means.

In testimony whereof, I have signed my name to this specification.

MAX REINER.
